UNITED STATES PATENT OFFICE.

HERMANN WEDER, SR., AND CHARLES HOWARD WOLFF, OF PHILADELPHIA, PENNSYLVANIA.

DOOR STOP AND HOLDER.

1,132,412.

Specification of Letters Patent.

Patented Mar. 16, 1915.

Application filed March 3, 1911. Serial No. 612,160.

To all whom it may concern:

Be it known that we, HERMANN WEDER, Sr., and CHARLES HOWARD WOLFF, citizens of the United States, residing at Philadelphia, in the county of Philadelphia and State of Pennsylvania, have invented certain new and useful Improvements in Door Stops and Holders; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in door holders, locks and stops and it proposes a device which is operative to stop the movement of a swinging door or to hold such a door at any desired position within a certain angle of its movement.

More particularly the improvement relates to that type of construction wherein cooperating companion elements are fitted on the door and door frame respectively, and the objects of the invention are to provide a device of the character stated which shall be of extremely simple and inexpensive construction; easily and quickly manipulated; compact and of neat and inconspicuous appearance; and capable of being folded out of the way when its use is not required so as to take up less room and to allow of a full opening of the door.

The invention is illustrated in the accompanying drawings, wherein:—

Figure 1 is a front elevation of the device applied; Fig. 2 is a horizontal section on line 2—2 of Fig. 1, showing device in inoperative position; Fig. 3 is a similar view, showing said device in operative position; Fig. 4 is a vertical section on line 4—4 of Fig. 3; Fig. 5 is a detail perspective view of one member of the device; Fig. 6 is a similar view of companion member; Fig. 7 is a front elevation of a modified form in position for use; Fig. 8 is a similar view showing the device locked in an inoperative position; Fig. 9 is a similar view showing the position of parts preparatory to swinging the device to operative position; Fig. 10 is a vertical section on line 10—10 of Fig. 7; Fig. 11 is a horizontal section on line 11—11

of Fig. 8; Fig. 12 is a detail perspective of one of the members of the device.

Similar characters of reference designate corresponding parts throughout the several views.

The companion parts to which a general reference has been made are designated by the numerals 1 and 2 and are fitted individually to the door A and door frame B respectively. Each of the companion parts consists of a sector-shaped plate its edge having an arc of 90° and provided along one of its straight edges with an integral attachment flange 3 which is secured by screws or otherwise to the door or door frame as the case may be. The parts 1 and 2 are arranged in immediately contiguous relation in such manner that their curved edges define a half circle when the door is closed, and the part 1 is arranged in a slightly higher plane than the part 2 so as to overlie the latter throughout a movement of the door.

The part 1 is provided near its outer corner with an opening 4 and at some distance inwardly from the opening with an indentation 5. A leaf spring 6 is pivoted upon the upper face of the part 1 near the side edge of the latter and is provided with a struck-out lug 7 and with a finger piece 8 which projects beyond the curved edge of the part 1. The tendency of this leaf spring is to move toward the part 1 and owing to this tendency the lug 7 will be engaged either in the opening 4 or in the indentation 5 according to the position of the leaf spring. The pivotal movement of the latter toward the side edge of the part 1 is limited by a projection 9 which is struck up from said side edge at a suitable point thereon. The part 2 is provided adjacent its curved edge and concentric thereto with a row of openings 10, each of which is radially elongated.

To use the device as a door stop the spring 6 is set so that its lug 7 engages in the indentation 5. This allows of an unretarded movement of the door through an angle of 90° *i. e.* from its closed position to a position where it strikes against the companion part that is secured to the door frame. When the device is thus used as a door stop the engagement of the lug 7 in the indentation 5 will prevent any displacement of the

spring or accidental operation of the device as a holder, which might be otherwise incident to jars and slamming of the door were the indentation 5 not provided.

5 To use the device as a door holder, the spring 6 being positioned as stated, the door is first moved to the position at which it is to be held, and thereupon said spring is turned on its pivot until it engages the projection 9 at which time, the spring being released, its lug 7 will move through the opening 4 and the particular opening 10 which is aligned with the opening 4 in accordance with the position of the door.

10 15 Owing to the engagement of the lug 7 in the aligning openings aforesaid further movement of the door in either direction will be prevented. Obviously by pressing the spring upwardly to disengage its lug 7 from the openings 4 and 10 the locking relation of the parts is disestablished and the door may again be moved to any position desired. By the provision of the opening 4 in addition to the openings 10 the locking engagement of the lug is more rigidly maintained and the liability of the lug to canting or distortion is rendered negligible.

15 In addition to the functions of the device as a door holder and stop it serves the further function of a lock and is analogous 30 in this respect to the so-called "door chains" commonly employed. In this function, the door is of course in its closed position, and the lug 7 of the finger is engaged through the opening 4 and is in the path of the plate 2, thereby preventing any material or substantial movement or opening of the door.

20 While the improvement has been described 40 as a door holder and stop it will be understood that it is applicable for use in analogous environments where it may be desired to lock a swinging part at different positions in a certain range of movement. 45 For example the device may be used as a shutter holder and lock, the plate 1 being secured to a suitable part of the window frame and the plate 2 being secured to the shutter.

50 The openings 10 are, as has been stated, radially elongated and are of considerably greater radial length than the opening 4. The purpose of this arrangement is to compensate for variations in the plane of the 55 face of the door frame with relation to the door. That is to say, the door frame or molding as it is sometimes called may not be flush with the door but may be set either slightly inwardly of the plane of the door or slightly beyond said plane and the length of the openings 10 is sufficient to provide for the engagement of the lug 7 in said openings regardless of the relation of the door frame and the door.

65 The modified or alternative construction

shown in Figs. 7, 8, 9, 10, 11 and 12 is the same in its essential principles of relation and operation as the construction shown in Figs. 1-6. In this latter example, however, the integral flanges 3 are not employed. Instead attachment plates 3^a are provided which are connected by hinge joints 11 to the sector-shaped plates 1 and 2. The plates 3^a are secured to the door and the door frame and the plates 1 and 2 are movable 70 on the hinge joints 11 into horizontal planes perpendicular to the planes of the plates 3^a or into vertical planes co-incident with the planes of the plates 3^a. When the device is to be used as a door stop either or both of 80 the plates 1 and 2 are positioned in their horizontal planes and both of said plates are so positioned when the device is to be used as a door holder. When the use of the device for either of these purposes is not 85 desired, the plates 1 and 2 are positioned in their vertical planes, being folded back against the parts with which they are associated. Means is provided for locking the plates 1 and 2 in either of the two positions 90 aforesaid. This means preferably embodies a slide 12 which is associated with the exposed face of the plate 3^a and has an extended finger piece 13 by which said slide may be manipulated. This finger piece is 95 provided along its inner edge with a slot or recess 14 and with a lip 15 overhanging said slot or recess 14. Assuming that the plate 1 or 2 as the case may be is in its vertical position, the slide 12 is moved inwardly so 100 that its lip 15 overlies said plate and thereby prevents the latter from accidentally dropping to its horizontal position. If on the other hand it is desired to lock said plate 1 or 2 in its horizontal position, the 105 slide is first moved outwardly until its lip clears the plate and thereupon the latter is swung downwardly as far as its hinge joint will permit at which time the slide is pushed inwardly so as to engage its lip over the 110 plate, the edge portion of the latter engaging in the slot or recess 14 and the plate by virtue of such engagement being positively held against accidental movement on its hinge joint.

115 The simplicity, compactness, cheapness, and convenience of the device are thought to be apparent from the foregoing description. It may be noted that in addition to these advantages the device possesses great 120 strength, amply sufficient for the purposes contemplated, owing to the shape and proportions of the plates 1 and 2, and to the fact that the attachment flanges or plates by 125 which said plates 1 and 2 are secured are co-extensive with one of the straight edges of the latter and are secured by a number of screws to the door or door frame as the case may be. The lines of stress are co-incident with the planes of the plates 1 and 2 and are 130

efficiently resisted by the latter on account of the characteristics mentioned.

Having fully described our invention, we claim:—

- 5 1. A door stop and holder comprising a pair of companion plates adapted for attachment to the door and door frame respectively, the one above the other, a leaf spring pivoted on one of the plates and tending to move toward the same, the leaf spring being provided with a lug and the plate carrying the leaf spring being provided with an opening through which the lug may pass, the other plate having openings arranged 10 in a curved row and the lug being adapted for engagement in any one of said last named openings.
- 15 2. A door stop and holder comprising a pair of companion plates adapted for attachment to the door and door frame respectively, the one above the other, and a leaf spring pivoted on one of the plates and tending to move toward the same, the leaf spring being provided with a lug, the plate carrying the leaf spring being provided with an opening through which the lug may pass, with an indentation in which the lug may engage and with a projection to limit the pivotal movement of the leaf spring as the 20 latter is manipulated to bring its lug from the indentation to the opening, the other plate having openings arranged in a curved row and the lug being adapted for engagement in any one of said last named openings.
- 25 3. A door stop and holder comprising a pair of companion plates adapted for attachment to the door and door frame respectively, the one above the other, a spring pressed lug provided on one of the plates, the other plate having openings arranged in a curved row and the lug being adapted for engagement in any one of said openings, a hinged attachment plate carried by each of 30 said companion plates, and means for holding each companion plate in either of two planes with relation to its attachment plate.
- 35 4. A door stop and holder comprising a pair of companion plates adapted for attachment to the door and door frame respectively, the one above the other, a leaf spring pivoted on one of the plates, the other plate having openings arranged in a curved row and the lug being adapted for engagement in any one of said openings, a hinged attachment plate carried by each of 40 said companion plates, and means for holding each companion plate in either of two planes with relation to its attachment plate.
- 45

tively, the one above the other, a spring 50 pressed lug provided on one of the plates, the other plate having openings arranged in a curved row and the lug being adapted for engagement in any one of said openings, a binged attachment plate carried by each of 55 said companion plates, and means for holding each companion plate in either of two planes with relation to its attachment plate, the means comprising a slide associated with each attachment plate and having a projecting finger piece provided along its inner edge with a recess, and with a lip overhanging the recess, and the lip being designed to lie over or to engage over the corresponding companion plate in accordance with the position of the latter with respect to its attachment plate.

5. A door stop and holder comprising two companion elements, one of which is provided with means for locking engagement 70 with the other, the elements being adapted for attachment to the door and door frame respectively, a hinged attachment plate carrying each element and means for holding each element in either of two planes with 75 relation to its attachment plate.

6. In a device of the character set forth, an attachment plate adapted to be secured to a door or a door frame, a plate hingedly connected to the attachment plate, and means for holding the last named plate in either of two positions with relation to its attachment plate, the means comprising a slide associated with the attachment plate and having a projecting finger piece provided along its inner edge with a recess and with a lip overhanging the recess, the lip being designed to lie over or to engage over the second named plate in accordance with the position of the latter with respect to the 80 attachment plate.

In testimony whereof we affix our signatures in presence of two witnesses.
